(57) **CLAIM**

We claim the ornamental design for a child-resistant medication container assembly, as substantially shown and described.

DESCRIPTION

FIGS. 1-8 are various views of a child-resistant medication container assembly in accordance with the present design. The assembly is adapted to contain a plurality of doses of medication therein.

FIG. 1 is a front perspective view of a child-resistant medication container assembly, shown in a closed position. FIG. 2 is a top view thereof.

FIG. 3 is a front view thereof.

FIG. 4 is a left side view thereof.

FIG. 5 is a right side view thereof.

FIG. 6 is a rear view thereof.

FIG. 7 is a bottom view thereof; and,

FIG. 8 is a front perspective view of the child-resistant medication container assembly, shown in an open position. Features disclaimed with broken lines (i.e., dash-dash lines) in the Figures indicate structure which forms no part of the claimed design. Features defined by dash-dot-dash lines in the Figures indicate lines of perforation between panels in the claimed design.
